UNITED STATES PATENT OFFICE.

HENRY BRUNN, OF BUFFALO, NEW YORK.

CARRIAGE-POLE.

SPECIFICATION forming part of Letters Patent No. 634,550, dated October 10, 1899.

Application filed July 31, 1899. Serial No. 725,619. (No model.)

To all whom it may concern:

Be it known that I, HENRY BRUNN, a citizen of the United States, residing at Buffalo, in the county of Erie and State of New York, have invented new and useful Improvements 5 in Carriage-Poles, of which the following is a specification.

This invention relates to a tip which is secured to the rear end of a carriage-pole and 10 inserted in the pole-socket.

The object of my invention is to construct this tip in such manner that it can be snugly fitted in the socket, so that the rear end of the pole is held steadily in the socket and 15 rattling and wear of the parts are prevented.

In the accompanying drawings, Figure 1 is a longitudinal section of the rear end of a carriage-pole provided with my improved tip and inserted in the pole-socket. Fig. 2 is a side 20 elevation of the rear end of the carriage-pole and tip. Fig. 3 is a cross-section in line 3, 3, Fig. 1.

Like letters of reference refer to like parts in the several figures.

25 A represents the rear end of a carriage-pole, and B the pole-socket, which is secured to the carriage or other vehicle and which supports the rear end of the pole. This socket may be of any suitable or well-known construction 30 and secured to the carriage in any suitable manner.

The rear end of the pole is provided with a metallic tip C, extending rearwardly from the pole and carrying a yielding or expansible 35 head D. The tip C is provided in its front side with a socket c, which receives the rear end of the pole, and in its rear side with a socket d, which receives the front portion of the head D. The latter is made of yielding 40 rubber or other suitable material and provided with a central longitudinal opening e, which permits the head to be applied to a screw-bolt F, projecting rearwardly from the body or partition g of the tip D. This screw-bolt is provided at its front end with a head 45 f and square shank f', which are seated in corresponding openings in the partition g; but it may be secured to the tip in any other suitable manner. The bolt extends rearwardly through the socket d of the tip and 50 beyond the same. A screw-nut h and washer h' are applied to the rear end of this screw-

bolt and bear against the rear end of the head D. The latter is of straight cylindrical form in its normal condition. By tightening the 55 screw-nut the head is compressed longitudinally and bulged out in rear of the tip until it projects beyond the peripheral face of the rear portion of the tip. The latter is somewhat smaller in diameter than the internal 60 diameter of the socket. For fitting the tip to the socket the expansible or yielding head is compressed until its bulging part has become so large in diameter that it fits snugly in the socket, as represented in Fig. 1. When 65 the tip is now inserted into the socket, the yielding head alone comes in contact with the socket, while the adjacent metallic part of the tip being smaller in diameter than the socket is kept out of contact with the latter. 70 The pole is by this means tightly held in the socket, thereby avoiding rattling and the wear which results from looseness of the parts.

When the bulging part of the flexible head has become compressed by long-continued 75 use, it can be readily expanded to again closely fit the socket by tightening the nut on the screw-bolt.

I claim as my invention—

1. The combination with a carriage-pole, of 80 a yielding head secured to the rear end of the pole and adapted to be inserted into the pole-socket, said head having its outer surface projecting beyond the adjacent portion of the pole and holding the same out of contact with 85 the socket, substantially as set forth.

2. A carriage-pole provided at its rear end with a tip having a yielding head and means whereby said head can be expanded to fit the pole-socket, substantially as set forth. 90

3. A carriage-pole provided at its rear end with a tip provided with a screw-bolt projecting rearwardly from said tip, a yielding head arranged upon said bolt, and a screw-nut applied to said bolt and bearing against the rear 95 end of said head for compressing and expanding the latter, substantially as set forth.

Witness my hand this 28th day of July, 1899.

HENRY BRUNN.
